UNITED STATES PATENT OFFICE.

HIPPOLYTE PARODI, OF PARIS, FRANCE.

CONTACT RAIL FOR ELECTRIC TRACTION.

Application filed June 15, 1922. Serial No. 568,640.

To all whom it may concern:

Be it known that I, HIPPOLYTE PARODI, citizen of the Republic of France, and resident of Paris, France, have invented a new and useful Contact Rail for Electric Traction, which improvements are fully set forth in the following specification.

This invention relates to a contact rail for electric traction.

10 In all systems of current collecting with three rails, hitherto in use, the endeavour has been to effect the contact of one surface against another surface by using a rail of ordinary shape on the top of which 15 slides a contact shoe or skate. In reality however, contact is only established at a number of points, the position of which changes constantly with the electrical contact. Consequently the current is subject to 20 continual interruptions manifested by sparks and even by arcing.

On the other hand in the case of an overhead current-collecting rail, snow and sleet may be deposited on the surface of the rail, 25 thus forming a hard insulating crust which cannot always be scraped off or removed by the current-collecting shoe unless sufficient pressure is used, so that the shoe has a planing action on the rail.

30 The object of the present invention is a new construction of the current-collecting rail allowing the collection of high intensities of current, without the production of arcs or sparks, under all conditions of working which may be encountered.

In order to understand the invention more clearly reference is made to the accompanying drawing which shows the transverse section of a current-collecting rail by way of 40 example. In said drawing the rail comprises a rail body 1 of steel—the shape of which depends on the method of fixing adopted—and of a sectional area sufficient to give the necessary conductivity. This rail body extends 45 upwardly in the form of a thin ridge 2 rounded off at the apex 3 which constitutes the line of contact proper against which the shoes bear.

The contact of the shoes is linear, as is 50 the case with a trolley wire, and not over a surface. The points of mechanical and electrical contact thus coincide and excellent contact can be assured however much the current-collecting shoe may suffer displacement.

Snow cannot accumulate in large quanti-

ties on the rounded apex and any layer of sleet which may form will always be too small to possess any great mechanical strength and will be brushed off and broken up by the brushing action of the shoe. Moreover, in the case of sleet, the heat produced by the arc would melt the ice in the immediate neighbourhood of the point, where a new contact is about to be established by the movement of the shoe, thus preventing interruption of the electrical contact along the line.

What I claim and desire to secure by Letters Patent is:—

1. Contact rail for electric traction, allowing currents of great intensities to be collected efficiently under all conditions, said contact rail comprising a rail body provided with shoulders and with a thin rounded extension to make linear contact with the current collecting means travelling thereover and to prevent the accumulation of snow and sleet on the contact surface of said rail body.

2. A contact rail for electric traction, allowing currents of great intensities to be collected efficiently under all conditions, said contact rail comprising an upwardly extending rail body having a thin ridge formed at its upper end, against the apex of which ridge current collecting means travelling thereover are adapted to bear.

3. Contact rail for electric traction, allowing currents of great intensities to be collected efficiently under all conditions, said contact rail comprising an upwardly extending rail body having a thin ridge formed at its upper end rounded-off at its apex against which the current collecting means travelling thereover are adapted to bear.

4. Contact rail for electric traction, allowing currents of great intensities to be collected efficiently under all conditions, said contact rail comprising an upwardly extending rail body provided with shoulders and having a thin ridge formed at its upper end, against the apex of which ridge the current collecting means travelling thereover are adapted to bear.

In testimony whereof I have signed this specification in the presence of a subscribing witness.

HIPPOLYTE PARODI.

Witness:

CHARLES LEON LOISEL.
